UNITED STATES PATENT OFFICE.

HYMAN MAIMIN AND HENRY B. BÄTJER, OF NEW YORK, N. Y., ASSIGNOR TO H. MAIMIN CO., INC., A CORPORATION OF NEW YORK.

CLOTH-CUTTING MACHINE.

1,284,402.

Specification of Letters Patent. Patented Nov. 12, 1918.

Application filed February 14, 1917. Serial No. 148,537.

To all whom it may concern:

Be it known that we, HYMAN MAIMIN, a citizen of the United States, and HENRY B. BÄTJER, a subject of the Emperor of Germany, both residing in the city, county, and State of New York, have invented certain new and useful Improvements in Cloth-Cutting Machines; and we do hereby declare the following to be a full, clear, and exact description of the invention, such as will enable others skilled in the art to which it appertains to make and use the same.

This invention relates to cloth cutting machines of the reciprocating knife-type, and more particularly provides an improved structure for guarding the knife when cutting and for sharpening the knife between cutting operations, whereby the machine may be quickly and easily rearranged to adapt the knife for cutting or sharpening as often as may be desired during a single cut.

The knife of a cloth cutting machine of the reciprocating-knife type requires very frequent sharpening. The machines are used for long cuts, so that the operator is obliged to remove the knife guard attachment from the knife and apply a sharpening implement to the edge of the knife blade, a number of times in a single cut. As commonly constructed the knife guard attachment comprises a pivotally mounted structure which is arranged to protect the knife during cutting, but which must be swung up out of the way when the knife is to be sharpened. Various kinds of sharpening attachments are employed, it being well known to pivotally mount the sharpening attachment on the machine so that the attachment can be moved out of the way and out of the line of vision of the operator, when not in use. Such a sharpening attachment may be provided with a pair of revolvably mounted stones adapted to be manually rotated to sharpen the knife by means of a handle geared to the stones and turned by the operator when the attachment is lowered into operative adjacency to the knife. According to these previous constructions, it has been found necessary, every time the knife needed sharpening, to swing the knife guard away from the knife, then lower the sharpening attachment and operate the same by means of its handle while maintaining the knife guard out of the way, then raise the sharpening attachment and

secure it in place, and then again lower the knife guard into operative relation to the knife, all these operations having to be performed in proper sequence a number of times in a single cutting and constituting with the rapidly reciprocating knife a very serious source of danger to the fingers of the operator.

According to the present invention, means are provided for operatively connecting the knife guard and sharpening attachments so that when one of the attachments is moved toward the knife blade the other is automatically moved away from the knife blade, and vice versa.

In its preferred form, the invention also makes provision for the fact that the support to which the knife guard attachment is pivoted is usually vertically adjustable on the machine in order that the stripper foot carried by the knife guard may be set properly for the thickness of the pile of goods to be cut, whereas the sharpening attachment is pivotally attached to some fixed part of the machine. Accordingly, the invention in its preferred form provides means including elements respectively fixed to the sharpening attachment, to the knife guard attachment and to the adjustable support on which the knife guard attachment is pivoted, for operatively connecting the knife guard and sharpening attachments in such a way that when one of the attachments is moved toward the knife blade the other is automatically moved away from the knife blade, and vice versa, irrespective of the vertical adjustment of the support.

The invention will be understood more clearly from the following description when taken in connection with the accompanying drawings illustrating two possible embodiments of the invention.

In these drawings Figures 1 and 2 are respectively side and front elevations of a cloth cutting machine with one embodiment of the invention applied thereto, these views illustrating the guard members of the knife guard attachment swung up and cleared out of the way on opposite sides of the knife and the sharpening attachment lowered into operative relation to the knife; Fig. 3 is an enlarged detail view showing certain of the parts as disclosed in Fig. 2; Fig. 4 is a view similar to Fig. 3, but showing said parts as disclosed in Fig. 1; Fig. 5

is a section on line 5—5 of Fig. 3; Fig. 6 is a section on line 6—6 of Fig. 4; Fig. 7 is a view generally similar to Fig. 4 but showing another embodiment of the invention, this view being partially in section as indicated by the line 7—7 of Fig. 8; Fig. 8 shows the arrangement of Fig. 7 in front elevation with certain of the parts removed; Fig. 9 shows in front elevation the pivoted arm to be actuated by a swinging movement of the sharpening attachment, and carrying a male wedge member to coact with the pair of symmetrical wedge members secured to the knife guard attachment; Fig. 10 is a compound view illustrating one of said symmetrical wedge members, such member being shown to the left in front elevation and to the right in side elevation; Fig. 11 is a bottom plan view of the pair of members as arranged in Fig. 8; and Figs. 12 and 13 are detail views taken on the lines 12—12 and 13—13 of Fig. 9.

Referring to the embodiment shown in Figs. 1 to 6, a knife guard attachment of the well-known flying wing type comprising the two guard members 14, and a sharpening attachment 15, are swingingly mounted on the machine in the familiar way. The details of construction of the sharpening attachment 15 are described and claimed in a copending application Ser. No. 148,536, filed by us on February 14, 1917. The details of construction of the complementary stripper-foot sections carried by the swinging ends of the guard members 14 are disclosed and claimed in another copending application, Ser. No. 148,538, filed by Hyman Maimin on February 14, 1917. Therefore it will be understood that the present invention does not concern itself with the particular sharpening mechanism of the sharpening attachment or with the particular design of the stripper foot structure carried by the knife guard attachment.

As indicated at 14^a in broken lines in Fig. 1, the stripper foot structure is adapted to press down on the pile of goods being cut, and hold down the pile to prevent the same from clinging to and rising with the reciprocating knife 16 on the up-strokes thereof, when the knife guard attachment is lowered and the machine is cutting.

As is well known, the knife guard attachment is pivotally mounted on a support 17, which is vertically adjustable on a guide 17^a so that the swinging arc of the knife guard attachment may be relocated as desired to correspond with the thickness of any particular pile of goods about to be cut; the thumb-screw 18 being provided to clamp the support 17 as adjusted. These guard members 14 are secured to intermeshing spur gears 19, so that the knife guard attachment may be conveniently raised or lowered by raising or lowering

either of the guard members. The sharpening attachment 15 is pivoted on a permanently fixed bracket 20 secured to the lower end of the guide 17^a. It will be observed that while the guard members 14 of the knife attachment are pivoted to swing in a plane normal to the plane of the knife blade, the sharpening attachment is pivoted to swing in a plane parallel to the plane of the knife blade. 75

The following mechanism is provided for moving the knife guard attachment or the sharpening attachment away from operative position, automatically, as the other attachment is manually moved toward operative position. One of the gears 19 is fast on its shaft 21 (see Fig. 4) and this shaft is prolonged so that a bevel gear 22 may be secured thereon in position to mesh with a similar gear 23 on a vertical shaft 24. This gear 23 is mounted on the vertical shaft to turn therewith, the gear having an integral hub 23^a journaled in an extension 25 offset from the vertically adjustable support 17. Also secured to the vertical shaft 24 to turn therewith, is another bevel gear 26. The flat under face of this gear 26 is supported on an extension 27 offset from the bracket 20, in which extension the lower end of the vertical shaft 24 is journaled. Bevel gear 26 meshes with a bevel gear 28 fixed on one end of a shaft 29 also fixed to the sharpening attachment and by which this attachment is pivoted to bracket 20. 90

In order that the various bevel gears 22, 23, 26 and 28, and the two spur gears 19 may always constitute an operative gear-train to connect the knife guard attachment and the sharpening attachment whereby when one attachment is moved away from operative position the other will move toward operative position, and at the same time to permit the adjustment of the support 17 on guide 17^a to be varied as desired to adapt the stripper foot carried by the knife guard attachment to any particular pile of goods to be cut, the bevel gear 23 is not fixed on the vertical shaft 24 but is merely keyed thereon, as indicated at 30 in Fig. 2. As a result, it will be observed that the two bevel gears 23 and 26 on the vertical shaft 24 always constitute parts of the operative gear-train, although one of said bevel gears is bodily movable relative to the other. 105 110 115

In operation, either one of the two guard members 14, or the sharpening attachment, as is most convenient, may be raised or lowered, to substitute one of such attachments for the other. As indicated clearly in Fig. 1, where the thumb screw 18 is shown easily accessible even with the sharpening attachment 15 thrown up, the knife guard attachment may be readily adjusted to set the stripper foot structure for any desired 120 125 130

height above the machine's base-plate. If desired, the support 17 and guide 17^a may be suitably calibrated to further facilitate setting the stripper foot structure, irrespective of which attachment is up and which down. The various gears constituting the gear train for operatively connecting the two attachments, are so designed that a swinging movement in either direction of the 5 knife guard attachment or of either guard member 14 will never be interfered with by any other part of the machine, no matter how the stripper foot structure is adjusted.

Referring now to the embodiment of the 10 invention illustrated in Figs. 7 to 13, the vertically adjustable support 17 on the guide 17^a has pivotally mounted thereon the spur gears 19 to which are secured the knife guard members 14. The lower end of the 15 guide 17^a has secured thereto a bracket 31 carrying a pair of ears 32 between which the sharpening attachment 15' is pivoted as indicated at 15''. Adjacent to its pivoted end the sharpening attachment is provided with 20 a cam 33 to coact with a bent-wire member 34 pivotally mounted on the support 17 by means of a hinge-pair comprising members 35 and 36, the two members being pivoted together at 37, with the members 36 secured 25 to the upper end of the support 17 and the member 35 loosely sleeving the bent-wire member 34. The inner end of the horizontally offset portion of bent wire member 34 is always within a vertically elongated slot 38 formed in bracket 31 between ears 32. The amount of play afforded such inner end of the bent-wire member 34 by the length of the slot 38, is just sufficient to permit the 30 bent-wire member to assume its broken line position when the sharpening attachment 15' is swung down to assume its broken line position. The arrangement of the parts is such that the cam 33 will force the bent wire member 34 to assume substantially its broken 35 line position every time the sharpening attachment 15' is lowered to operative position relative to the knife (not shown), irrespective of the vertical adjustment of the support 17 on the guide 17^a.

50 The following means are provided to automatically move the guide members 14 of the knife guard attachment away from the knife, when the member 34 is swung in as described by a lowering of the sharpening attachment. A male wedge member 39 is loosely sleeved on bent-wire member 34, and is arranged to coact with a pair of symmetrical wedge members 40 mounted on arms 41 secured to gears 19 and guard members 14. The breast of the wedge member 39 is always seated in a pocket 42 formed by a pair of similar recesses cut in the opposed side faces of the pair of symmetrical wedge members 40. A retractile spring 43, attached at its opposite ends to the two

wedge members 40 as indicated in Figs. 8 and 10, normally holds the wedge members 40 as illustrated in full lines, and the knife guard attachment is thereby maintained in effective relation to the knife. A cup 44 is mounted on member 34 for receiving one 70 end of an expansile spring 45. This cup 44 will always be opposite a cup 46 formed on support 17 for receiving the other end of spring 45, because the cup 44 is on a sleeve 75 formed integral with the portion of wedge member 39 which sleeves member 34, which wedge member will always be locked against vertical movement relative to the symmetrical wedge members 40, as will be understood, by means of the pocket 42; irrespective of the vertical adjustment of support 17 on guide 17^a. The expansile spring 45 serves to urge the lower portion of the bent wire member 34 yieldingly against the 80 cam 33 at all times.

The operation of the embodiment just described should be obvious. Each time the sharpening attachment is lowered into operative adjacency to the knife, the bent-wire 90 member 34 is forced to assume the broken line position of Fig. 7, with the result that wedge member 39 forces wedge members 40 sufficiently apart to cause the knife guard members 14 to assume approximately the 95 positions indicated in broken lines in Fig. 8. After the stones of the sharpening attachment have been applied to the knife edge, and when the sharpening attachment is swung up above the knife, the retractile 100 spring 43 returns the guard members 14 to operative position relative to the knife as indicated in full lines in Fig. 8. At the same time, the wedge members 40 are again brought together to reestablish the pocket 105 42; and the expansile spring 45 causes the bent-wire member 34 to follow the cam 33 as such cam moves from the broken line position to the full line position of Fig. 7. The springs 43 and 45 and the other parts 110 are so proportioned and designed that the spring 43 is never able to cause the wedge member 39 to bind between the wedge members 40 during the withdrawal of the wedge member 39. Nevertheless, the three wedge 115 members are always held against relative vertical movement due to the way in which the wedge member 39 is always engaged by the top and bottom walls of the recesses which form the pocket 42; and thereby an 120 operative train of mechanism is always interposed between the two attachments to attain the objects of the invention irrespective of the vertical adjustment of the support 17 on the guide 17^a.

125 We claim:

1. In a cloth cutting machine of the kind described, the combination of a knife guard attachment, a sharpening attachment, each attachment being mounted for movement 130

from an operative to an inoperative position and vice versa, and means partially carried by each of the attachments and operatively connecting them together so that when one attachment is moved from operative position the other is moved toward operative position.

2. In a cloth cutting machine of the kind described, the combination of a pivoted knife guard attachment, a pivoted sharpening attachment, each attachment adapted to be swung into operative adjacency to the knife blade when the other is out of operative adjacency thereto, and means operatively connecting the two attachments for causing a swinging movement of the knife guard attachment away from the knife blade when the sharpening attachment is swung in toward the knife blade.
3. In a cloth cutting machine of the kind described, the combination of a knife guard attachment, a support vertically adjustable on the machine and to which the attachment is pivoted, a sharpening attachment pivotally mounted on the machine, and mechanism for always causing a pivotal movement of the knife guard irrespective of the adjustment of the support when the sharpening attachment is moved on its pivot.
4. In a cloth cutting machine of the kind described, the combination of a knife guard attachment, a support adjustable on the machine and to which the attachment is pivoted, a sharpening attachment pivotally mounted on the machine, and a gear train for operatively connecting the two attachments in various adjustments thereof and in various adjustments of the support, the gear train including a gear fixed on the sharpening attachment, a gear fixed on the knife guard attachment and a gear carried by the support.

5. In a cloth cutting machine of the kind described, the combination of a knife guard attachment comprising a pair of guard members each pivotally mounted to permit it to be swung away from the knife in a plane substantially normal thereto, a sharp-

ening attachment pivoted to permit it to be swung toward the knife in a plane substantially parallel thereto, and means carried partially by the knife guard and partially by the sharpening attachment whereby upon a manual swinging of the sharpening attachment to operative position relative to the knife, the guard members, are both cleared out of the way on opposite sides of the knife so as to avoid interference with the approach of the sharpening attachment toward the knife and also to avoid interference with manual actuation of the sharpening attachment when moved to operative position.

6. In a cloth cutting machine of the kind described, the combination of a pivoted knife guard attachment, a pivoted sharpening attachment, and a gear train including two elements, one of which is fixed to each of the two attachments, the two attachments being pivoted to swing in non-parallel planes.

7. In a cloth cutting machine of the kind described, the combination with the vertically adjustable knife guard support, of a knife guard attachment pivoted on said support, a sharpening attachment pivoted on another part of the machine, a gear fixed on the sharpening attachment, a gear fixed on the knife guard attachment, an intermediate gear always meshing with the gear on the sharpening attachment, another intermediate gear always meshing with the gear on the knife guard attachment, one of said intermediate gears being carried by the vertically adjustable support, and means always operatively connecting the two intermediate gears while permitting bodily movement of one intermediate gear relative to the other, whereby when one intermediate gear is rotated the other rotates irrespective of the vertical adjustment of said support.

In testimony whereof we affix our signatures.

HYMAN MAIMIN.
HENRY B. BÄTJER.
